CLAIM

The ornamental design for a three-dimensional scanner as shown and described.

DESCRIPTION

FIG. 1 is a top front perspective view of a three-dimensional scanner showing the new design;

FIG. 2 is a bottom rear perspective view thereof;

FIG. 3 is a left side elevational view thereof, the right side being a mirror image;

FIG. 4 is a front elevational view thereof;

FIG. 5 is a rear elevational view thereof;

FIG. 6 is a top plan view thereof; and,

FIG. 7 is a bottom plan view thereof.

The broken lines depict portions of the three-dimensional scanner which form no part of the claimed design.
